UNITED STATES PATENT OFFICE.

LEONARD V. HOSFORD, OF PORTLAND, OREGON.

FUEL NOZZLE FOR INTERNAL-COMBUSTION ENGINES.

Application filed October 11, 1926. Serial No. 141,009.

My invention has for its object to provide a new and useful fuel nozzle unit for internal combustion engines, particularly of the Diesel type, and it primarily has for its object to provide a nozzle with a removable nozzle proper so constructed that it will be comparatively inexpensive to make and maintenance costs will be a minimum.

More specifically the invention provides an improved nozzle unit so constructed that the danger of clogging is reduced to a minimum and so constructed whereby in the event that the oil escape openings become enlarged by the burning action of heat the fuel distributing nozzle may be ground further into its casing's seat and the diameter of the oil outlets be thus reduced to the proper area.

Another object of the invention is to provide a structure in which the nozzle core and the nozzle casing may be removed as a unit from the remainder of the device without the necessity of disassembling it in case it becomes necessary to clean or repair the parts.

More subordinately invention also resides in those novel features of construction, combination and arrangement of parts, all of which will be first fully described, then be specifically pointed out in the appended claims, reference being had to the accompanying drawing in which:—

Figure 1 is a vertical longitudinal section of a unit constructed in accordance with my invention.

Figure 2 is a detail elevation of the nozzle core member.

Figure 3 is a top plan view of the same.

Figure 4 is a detail vertical section of the nozzle core member's casing.

Figure 5 is a detail vertical section of the nozzle core and its casing member before the same are drilled to produce the outlet apertures.

Figure 6 is a view similar to Figure 5 with one outlet aperture finished and another partly drilled.

In the drawing, in which like numerals of reference indicate like parts in all the figures, 1 indicates the base of the unit which is provided with the usual bolt holes for attachment to a cylinder head and 2 indicates the upper casing part while 3 represents the cap nut that closes the upper end of the upper casing part 2.

A lower part 4 extends below the base 1

and has its end stepped and threaded to receive the nozzle holding cap 12 hereinafter again referred to.

The upper casing part 2 has a chamber 5 and the lower casing part 4 has a passage 6, the latter being provided with a valve seat 7. Between the chamber 5 and the passage 6 there is located a gland 8 and gland nut 9 to prevent communication between the chamber and the passage around the needle valve 27, the latter cooperating with the seat 7 to control the flow of lubricant from the source to the outlet nozzle.

The threaded end 10 of the lower casing part 4 is shouldered, as at 11, to fit the corresponding part of the cap 12, the cap 12 having the chamber 13 and bore 14 as indicated, the bore 14 being of lesser diameter than that of the casing 13 so as to conform to the nozzle casing sleeve 15.

The nozzle core 16 consists of a stem-like body and a head separated by an annular oil groove as shown. The nozzle core's stem is threaded, as at 17, and is provided with a central feed passage 18 having lateral passages 19 and oil grooves 20, the latter delivering into the annular groove 21 before referred to.

It will be seen that the nozzle casing sleeve 15 has a cone seat 24 to cooperate with the cone surface 25 of the nozzle core's head.

In order to produce the outlet ports of the nozzle I drill holes, the axes of which lie along the conical surfaces 24—25, the outlets being produced by a large drill to produce the external outlet portion 22 and a small drill to produce the inner parts of the passage numbered 23, the drill holes 22 and 23 being made partly in the sleeve 15 and partly in the head in the nozzle core as best indicated in Figures 5 and 6 of the drawing.

The end of the nozzle core has a cross slot 26 for a screw driver or valve grinding tool, by means of which the surfaces 24—25 may be ground together.

The needle valve 27 is held to its closed position by a collar 28 on the valve rod and a spring 29 interposed between the collar 105 and the cap nut 13.

30 designates the lead-in duct for delivering the oil from the source of supply through the base 1 to the passage 6.

It will be seen that when it is desired to clean or repair the nozzle end of the unit it is only necessary to unbolt the unit from the

- engine and unscrew the cap 12 when the parts 15 and 16 and jam nuts 31 may be removed from the cap 12. By loosening the jam nuts and inserting a small amount of valve grinding compound between the surfaces 24-25 those surfaces may be ground together to reduce the bores 22-23 and these bores may be redrilled if necessary to re-establish their proper proportions.
- 10 By unscrewing the nozzle core from the jam nuts the nozzle casing sleeve or bushing 15 may be taken off and replaced if necessary or desirable.

If the unit is attached to a removable cylinder head of an engine and the cylinder head is removed for the purpose of cleaning out carbon for example it will not be necessary to remove the unit from the cylinder head in order to clean the nozzle tip.

20 All that would be required would be to unscrew the nozzle core and remove it and the nozzle casing sleeve 15 from the inner side of the cylinder head. Then, after cleaning the passages in the nozzle core, the parts 25 may be restored by reversing the operation of removal.

Other advantages of my invention will be apparent to those skilled in the art.

What I claim is:

- 30 1. A fuel oil nozzle for internal combustion engines and the like, comprising a casing having an oil passage and provided with a threaded end, a nozzle holding cap threaded onto said threaded end, said cap having a chamber with a restricted outlet passage, a nozzle core-casing-sleeve located in said restricted outlet, jam nuts in said cap chamber and a nozzle core associated with said nozzle core-casing-sleeve and adapted to receive said jam nuts to secure said nozzle core and its casing-sleeve together, said nozzle core having fluid passages for conveying the fuel from said oil passage to atmosphere.
2. A fuel oil nozzle for internal combustion engines and the like, comprising a casing having an oil passage and provided with a threaded end, a nozzle holding cap threaded onto said threaded end, said cap having a chamber with a restricted outlet passage, a nozzle core-casing-sleeve located in said restricted outlet, jam nuts in said cap chamber and a nozzle core associated with said nozzle core-casing-sleeve and adapted to receive said jam nuts to secure said nozzle core and its casing-sleeve together, said nozzle core having a central bore communicating with said oil passage and extending inwardly from one end, and having oil outlet ducts communicating with said bore at its other end.
3. A fuel oil nozzle for internal combustion engines and the like, comprising a casing having an oil passage and provided with a threaded end, a nozzle holding cap threaded onto said threaded end, said cap having a

chamber with a restricted outlet passage, a nozzle core-casing-sleeve located in said restricted outlet, jam nuts in said cap chamber and a nozzle core associated with said nozzle core-casing-sleeve and adapted to receive said jam nuts to secure said nozzle core and its casing-sleeve together, said nozzle core having a central bore communicating with said oil passage and extending inwardly from one end, and having oil outlet ducts communicating with said bore at its other end, said nozzle core and its casing-sleeve having complementary conical seats and drill holes in communication with said oil grooves and with atmosphere for the purpose specified.

4. A fuel nozzle for internal combustion engines and the like, which comprises a casing having an oil passage and provided with a threaded lower end, a cap threaded on said lower end and having a chamber and a restricted outlet, a nozzle-casing-sleeve located in said restricted outlet, a jam nut in the cap's chamber, a nozzle core passing through said sleeve and having a head portion to engage the same and having a threaded portion to receive the jam nut, said nozzle core having means to pass oil from said oil passage to atmosphere.

5. A fuel nozzle for internal combustion engines and the like, which comprises a casing having an oil passage and provided with a threaded end, a cap threaded on said end and having a chamber and a restricted outlet, a nozzle-casing-sleeve located in said restricted outlet, a jam nut in the cap's chamber, a nozzle core passing through said sleeve and having a head portion to engage the same and having a threaded portion to receive the jam nut, said nozzle core having an oil passage communicating with the aforesaid oil passage and said sleeve and head portion having complementary conical seats with ducts to deliver the oil from said core's oil passage to atmosphere.

6. A fuel nozzle for internal combustion engines and the like, which comprises a casing having an oil passage and provided with a threaded end, a cap threaded on the lower end and having a chamber and a restricted outlet, a nozzle-casing-sleeve located in said restricted outlet, a jam nut in the cap's chamber, a nozzle core passing through said sleeve and having a head portion to engage the same and having a threaded portion to receive the jam nut, said nozzle core having an oil passage communicating with the aforesaid oil passage and said sleeve and head portion having complementary conical seats with ducts to deliver the oil from said core's oil passage to atmosphere, said nozzle core and sleeve oil passage and ducts including drill holes partly located in the sleeve and partly located in the head for the purposes specified.

7. In fuel spray nozzles wherein is pro-

vided a base having a threaded extension and a central passage with a valve seat, and a valve controlling said passage; a cap threaded on said threaded extension, said cap having a chamber to receive a portion of said threaded extension, jam nuts in said chamber held in place by engagement with said threaded extension when said cap is in position thereon, said cap having a reduced passage, a fuel nozzle sleeve located in said reduced passage and having a conical seat at its outer end, a nozzle core having a conical head to engage said conical seat and to

receive said jam nuts, whereby to hold said jam nuts and said sleeve and said nozzle core 15 together as a unit, said nozzle core having oil passages and said nozzle core and said sleeve having complementary drill hole portions, said drill hole portions being located to effect communication between said oil passages and the atmosphere and said oil passages being in communication with said central passage substantially as shown and for the purposes described. 20

LEONARD V. HOSFORD.
